(57) **CLAIM**

The ornamental design for a bag with metallic crepe, as shown and described.

DESCRIPTION

FIG. 1 is a front perspective view of the bag with metallic crepe wherein an interior bag is nested into an exterior bag showing our new design;

FIG. 2 is a front elevational view thereof, the back view being a mirror image thereof;

FIG. 3 is an exploded view thereof wherein the nested interior bag and exterior bag of FIG. 1 are shown separately for clarity of disclosure;

FIG. 4 is an enlarged view of a portion shown in FIG. 1 indicated by broken-line square 4;

FIG. 5 is a cross-sectional view of the portion shown in FIG. 4; and,

FIG. 6 illustrates the portion shown in FIG. 4 in a stretched configuration.

The broken lines showing a portion of the bag with metallic crepe is included for the purpose of illustrating environmental structure and form no part of the claimed design.
